Application filed October 6, 1894. Serial No. 525,165. Term of patent 3½ years.

To all whom it may concern:

Be it known that I, GEORGE F. GREENE, a citizen of the United States, residing at Providence, in the county of Providence and State of Rhode Island, have invented and produced a new and original Design for Scarf-Pins, of which the following is a specification, reference being had to the accompanying drawing, forming part thereof.

- 10 The head or ornamental portion of the scarf-pin has the outline, shape and appearance of a dancing man, in front view, clothed with knee breeches, a short skirted coat, stock-

ings, gaiters and a small round narrow-brimmed hat. His cheeks are distended and he appears to be playing, with both hands extended, on a hautboy. The pin tongue extends centrally downward from said ornamental portion or head.

What I claim is—

20 The design for a scarf-pin herein shown and described.

GEORGE F. GREENE.
